UNITED STATES PATENT OFFICE

WILLIAM L. EVANS, OF WASHINGTON, INDIANA

RING-JOINT MACHINE

Application filed May 10, 1929. Serial No. 362,059.

This invention relates to ring joint machines of the general type shown in my pending application, Ser. No. 360,769 filed May 6, 1929, and, among other objects, aims 5 to provide improved driving and manual control mechanism for the groove cutter and ring assembling ram. Another aim is to provide an improved turret mounting or support for the cutter and ram whereby they may be 10 quickly moved over the work, so that a joint may be completed in a few seconds. Other objects and advantages will appear in the specification, when considered in connection with the accompanying drawings, wherein.

Fig. 1 is a side elevation of a machine embodying the invention;

Fig. 2 is a front elevation of the machine;

Fig. 3 is a fragmentary elevation taken from the right hand side of Fig. 2;

Fig. 4 is a fragmentary vertical sectional view showing the groove cutter;

Fig. 5 is a top plan view;

Fig. 6 is a fragmentary sectional view showing a ring about to be assembled; and

Fig. 7 is a plan view of a typical corner joint made by the machine.

Referring particularly to the drawings, the machine there shown is supported on a vertical column 10 mounted on a suitable base 11. A work table 12 is adjustably supported on the column and the mechanism for cutting the ring grooves and assembling the rings is supported on the column above the table.

In the present example, both the cutter and ram are carried by a turret head 13 made of a single casting and having a vertical spindle or shaft housing 14 and gear casing 15 both supported by an integral bracket 16 mounted to swing on the column 10 between fixed collars 17.

As best shown in Fig. 4, a cutter spindle or shaft 18 is journaled for both sliding and rotating movement in the housing 14 and a groove cutter 19, preferably like that shown in my aforesaid application, is adjustably mounted on its lower end. The arrangement is such that the cutter may be lowered and fed into the work which is held on the table.

To drive the cutter spindle, a crown pulley 20 is mounted on its upper end and a motor

21 secured to a swinging bracket 22, which is arranged to swing with the turret head, has an elongated, smooth or cylindrical pulley over which a spindle driving belt 23 is trained. The idea is to permit the belt to ride 55 up or down on the elongated pulley as the spindle and its crown pulley are raised or lowered to feed the cutter into the work.

To provide for tightening the belt, the motor supporting bracket 22 is independently 60 adjustable on the column 10 and is adapted to be secured in adjusted position with respect to the turret bracket 16 by means of a bolt 24 passing through arcuate slots 25 in vertically alined ears 26 projecting from the 65 brackets 16 and 22 (see Fig. 5).

As in my aforesaid application, there is shown a shaving hood 27 cooperating with the groove cutter 19 and slidably mounted on the cutter spindle 18. Herein, a cross-head 28 is rotatably mounted on the spindle 18 above the shaving hood between a lower fixed collar 29 and an upper fixed collar 30, a suitable ball or roller bearing member 31 being interposed between the upper fixed 70 collar 30 and the upper end of the crosshead. A plurality of shaving cup supporting rods 32 having nuts 33 on their upper ends are suspended from the crosshead, and adjustably secured to the cover plate 34 of the shaving hood in screw threaded bosses 35. Coil springs 36 are interposed between the lower face of the crosshead and adjustable stop shoulders 37 on the screw threaded lower 75 ends of the rods. The arrangement is such 80 that the crosshead is lowered with the spindle, and causes the lower edge of the shaving hood to strike the upper face of the work before the cutter begins to operate. As the spindle is further lowered, the crosshead 85

exerts pressure on the springs 36, while the hood remains in engagement with the work, the gripping pressure upon the work increasing as the cutter is fed into it. As the cutter produces shavings, they are removed from 90 the hood by means of a small fan 38 above the cutter and fixed on the shaft or spindle, a suitable discharge spout 39 being provided at one side of the hood.

In Figs. 1, 3 and 4, the turret is shown 100

as having a vertical, downwardly extending apron 40. An integral ear or lug 41 on this apron is utilized as an additional lower bearing to steady the cutter spindle. On the rear face of the apron is pivoted an operating lever 42 connected by means of a suitable pin or bolt 43 passing through a vertical slot 44 to the crosshead 28. This connection between the lever and the crosshead prevents rotation of the crosshead with the cutter spindle. As will be seen in Figs. 3 and 4, the lever handle is easily accessible at the right hand side of the turret so that it can be manipulated by the right hand of the operator. It is normally held in its uppermost position, thereby holding the cutter in inoperative position by means of a small tension spring 45. (Fig. 1.)

Now referring to Figs. 2, 3 and 4, the cutter shaft or spindle is shown as being connected by reduction gearing to drive the ring assembling ram 46 in much the same manner as disclosed in my aforesaid application. Herein, a worm 47 is fixed on the shaft 18 within the shaft housing, and meshes with a worm gear 48 within the gear case, a crank 49 being provided on the shaft of the worm gear as shown in Fig. 2. A hand lever 50 having an integral arm 51 constituting a part of a toggle joint, is pivotally mounted on the crank pin. A ram rod or bar 52 is slidably mounted in bearings provided in a pair of spaced brackets or lugs 53 on the apron, and its upper end is connected to the arm 51 of the lever by a link 54 which is preferably bifurcated at its ends. This link 54 constitutes the other part of the toggle.

As will be seen in Fig. 4, the ram cup 46 is adjustably secured to the lower end of the ram bar and is normally held in its uppermost or inoperative position by means of a spring 55 between the lower bearing member 53 and a shoulder or stop member 56 on the bar. The arrangement is such that, when the lever 50 is lowered as shown in Fig. 2, the two arms or links of the toggle are almost, but not quite straightened, being prevented from swinging past the position shown by means of a suitable toe portion on the arm 51 cooperating with the bottom of the bifurcation in the upper end of the link 54 (Fig. 3). The lever is thus utilized initially to lower the ram to engage a ring 57, on the frusto-conical guiding block 58, as shown in Fig. 6. This is done preferably when the crank is in its uppermost position, so that when the crank rotates to its lower position, pressure will be exerted by it on the ram through the toggle, forcing the ring 57 over the guiding block 58 into the ring groove around the boss provided by the groove cutter. When the lever 50 is released, the spring 55 will raise the ram again to its inoperative position. Should the ram force the ring to the bottom of the ring groove before the crank reaches the lower end of its stroke, the toggle

arms will kick toward the right, as viewed in Fig. 2, and thereby provide a yielding connection to prevent destruction of the joint or breakage of the machine.

As set forth in my aforesaid copending application, the turret is adapted to be swung to either working position with the cutter or the ram properly centered over the work, it being understood that the work is placed on the table against a suitable gauge plate or guide (not shown). Herein, a stop member in the form of a collar 59 having radial arms 60 is secured to the column 10, and a spring urged plunger 61 projects through the turret apron 40 to limit the swinging movement of the turret by striking the arms.

To limit the depth of the grooves made by the cutter, there is shown an adjustable stop member 62 in the form of a screw threaded into the cover plate 34 of the shaving hood and held in adjusted position by means of a suitable lock nut 63 (Fig. 3). An integral lug or extension 64 on the crosshead is adapted to strike the upper end of the stop member when the crosshead and the cutter shaft are moved to feed the cutter into the work, while the hood 27 remains relatively stationary, having been blocked in its descent by engagement with the work.

From the foregoing description, it will be seen that the cutter may be quickly swung to operating position over the work and fed into it by pulling down on the hand lever 42 until the stop lug 64 strikes the stop member 62. Then the handle is released so that the cutter is raised to its uppermost position by means of the spring 45 assisted by the climbing action of the worm 47 on the worm gear 48, the threads on the worm being left handed to facilitate this climbing movement. The turret is then swung to the position shown in Fig. 4 with the ram properly centered over the work, the frusto-conical guide block with the ring on it is placed upon the boss provided by the cutter, and the ram is lowered to a position to be operated by the crank by means of the hand lever 50, which almost, but not quite, straightens the toggle links as shown in Fig. 2. The lever is lowered while the crank 49 is near the upper end of its stroke and is held down until the crank passes the lower part of its stroke, the power being applied through the toggle links. If the ram cup forces the ring to strike the bottom of the groove before the crank has reached the lower part of its stroke, the toggle links will kick to the right as hereinbefore described, and prevent destruction of the joint, as well as breakage of the ram operating mechanism. After the crank has lowered the ram, the hand lever 50 is released and the jointed parts are removed from the work table, so that the cycle of operations can be repeated. It will thus be seen that the groove cutting and ring assembling operations can be completed very

quickly. An unskilled laborer can very easily learn to operate the machine and can make a complete joint within approximately ten seconds.

From the foregoing description, it will be seen that the working parts of the machine are very simple and easy to manipulate. The machine is of relatively small weight, so that it can be moved to the work. This is especially desirable in connection with large building operations, where the trim is to be assembled on the job rather than at the lumber mill. The operation of the machine is so simple that an unskilled laborer or a boy can manipulate it. The cutter is never exposed, and cannot injure the operator, or catch his clothing. Furthermore, there are no rotating parts that expose the operator to any danger of serious injury.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:—

1. A ring joint machine, comprising, in combination, a work table; a turret above the work table; a groove cutter having a shaft slidably and rotatably mounted in the turret; a ring assembling ram slidably mounted with respect to the turret; power connections between the cutter shaft and the ram; a motor connected to drive the cutter shaft; and hand levers for lowering the cutter and ram to engage the work on the table.

2. A ring joint machine, comprising, in combination, a support having a vertical column; a work table on the column; a turret on the column above the work table; a groove cutter having a spindle slidably and rotatably mounted in the turret; a ring assembling ram slidably mounted on the turret; and a motor independently supported on the column and having a belt driving connection to said cutter shaft, said motor being adjustable around the column to tighten the belt.

3. A ring joint machine, comprising, in combination, a support having a vertical column; a work table on the column; a turret on the column above the work table; a groove cutter having a spindle slidably and rotatably mounted in the turret; a ring assembling ram slidably mounted on the turret; reduction gearing operatively connecting the cutter shaft to the ram; and a motor having a belt driving connection to said cutter shaft.

4. A ring joint machine, comprising, in combination, a base; a vertical column on the base; a work table supported on the column; a turret on the column above the work table; a groove cutter having a spindle slidably and rotatably mounted in said turret; means to raise and lower the cutter and its shaft; a

pulley on the shaft; a motor also supported to swing with said turret and having a driving pulley; a driving belt between said pulleys; a ring assembling ram on the turret adapted to be swung over the groove made by said groove cutter; and reduction gearing connecting said ram to be operated by said motor.

5. A ring joint machine, comprising, in combination, a base; a column on the base; a work table supported on the column; a turret on the column above the work table; a groove cutter and ring assembling ram carried by the turret and arranged to operate successively on the work; a bracket supported on the column to move with the turret; a motor secured to the bracket; a belt driving connection between the motor and cutter shaft; and power connections between the cutter shaft and ram.

6. A ring joint machine, comprising, in combination, a base; a column on the base; a work table supported on the column; a turret on the column above the work table; a groove cutter and ring assembling ram carried by the turret and arranged to operate successively on the work; a bracket supported on the column to move with the turret; a motor secured to the bracket; a vertically elongated pulley on the motor shaft; a cutter shaft extending through the turret and having a crown pulley aligned with the motor pulley; a belt trained over said pulleys arranged to permit the cutter shaft and its pulley to be raised and lowered; and power connections between the cutter shaft and the ram.

7. In a ring joint machine of the character described, a work table; a vertical column above the work table; a turret on the column; a groove cutter having a shaft slidably and rotatably mounted in the turret; a motor on the opposite side of the column from the groove cutter and connected to drive the cutter shaft; and a hand lever connected to the shaft to feed the cutter into the work.

8. In a ring joint machine of the character described, a work table; a column extending above the work table; a turret on the column; a groove cutter having a shaft slidably and rotatably mounted in the turret; a cross-head rotatably mounted on the shaft; a shaving hood around the cutter; suspending rods for the shaving hood slidably mounted in said crosshead; compression springs on said rods arranged to exert pressure on said hood when the cutter is lowered and cause the hood to grip the work; and a pivoted, spring urged lever on the turret connected to the crosshead to raise and lower the cutter, said connection preventing the crosshead from rotating with the shaft.

9. In a ring joint machine of the character described, a work table; a column extending above the work table; a turret on the column; a groove cutter having a shaft slidably and

rotatably mounted in the turret; a cross-head rotatably mounted on the shaft; a shaving hood around the cutter; suspending rods for the shaving hood slidably mounted in said crosshead; compression springs on said rods arranged to exert pressure on said hood when the cutter is lowered and cause the hood to grip the work; an apron on the turret adjacent to said shaft; a hand lever pivoted to the apron and connected to the crosshead to raise and lower the cutter shaft; a spring connected to the lever normally to hold the cutter in inoperative position; and adjustable stop means to limit the feeding movement of the cutter.

10. In a ring joint machine of the character described, a work table; a column extending above the work table; a turret on the column; a groove cutter having a shaft slidably and rotatably mounted in the turret; a cross-head rotatably mounted on the shaft; a shaving hood around the cutter; suspending rods for the shaving hood slidably mounted in said crosshead; compression springs on said rods arranged to exert pressure on said hood when the cutter is lowered and cause the hood to grip the work; an apron on the turret adjacent to said shaft; a hand lever pivoted to the spring and connected to the crosshead to raise and lower the cutter shaft; a spring connected to the lever to normally hold the cutter in inoperative position; and adjustable stop means associated with the hood and the crosshead to limit the feeding movement of the cutter and thereby regulate the depth of the grooves.

11. In a ring joint machine of the character described, a work table; a supporting column extending above the work table; a vertical shaft housing supported on the column above the table; a groove cutter having a shaft both slidably and rotatably mounted in the housing; driving means for the shaft; a non-rotatable shaving hood surrounding the cutter and arranged to be lowered to engage and grip the work as the cutter is fed toward the work; and a lever connected to raise and lower the cutter and hood.

12. A ring joint machine, comprising, in combination, a work table; a supporting column extending above the table; a head mounted on the column; a rotary groove cutter and a ring assembling ram slidably mounted on the head and arranged to be moved into engagement with the work on the table; levers connected to feed the cutter and to initiate the operation of the ram; and a source of power to operate both the cutter and the ram.

13. A ring joint machine, comprising, in combination, a work table; a supporting column extending above the table; a turret head on the column; a rotary cutter having a shaft slidably mounted in the turret head; a ring assembling ram also slidably mounted on the head; stop means to enable the turret head

to be swung and bring the cutter or the ram over the work on the table; power means connected to drive the cutter and the ram; and hand levers connected to move the cutter and the ram toward the work.

14. A ring joint machine, comprising, in combination, a work table; a supporting column extending above the table; a turret head on the column; a rotary cutter having a shaft slidably mounted in the turret head; a ring assembling ram also slidably mounted on the head; a stop member on the column; a plunger on the turret head engaging the stop member whereby the turret head may be swung and stopped to center the cutter or the ram over the work; a motor mounted to move with the turret and having a belt driving connection to the cutter shaft; means to deliver power from the motor to the ram; and hand levers to lower the cutter and the ram and cause them to operate on the work.

15. In a ring joint machine of the character described, a work table; a turret above the table; a ring assembling ram slidably mounted on said turret; a power operated crank for the ram; a manually operable toggle joint between the crank and the ram; and a spring associated with the ram normally to hold it in inoperative position.

16. In a ring joint machine of the class described, a work table; a vertical column above the work table; a turret mounted on the column; a rotary groove cutter and a ram carried by the turret; a bracket on the column adjacent to the turret and adjustable about the column; a motor supported on the bracket; a belt driving connection between the motor and the cutter shaft; and means for adjusting the bracket with respect to the turret, whereby to tighten the driving belt.

In testimony, that I claim the foregoing as my own, I have hereto affixed my signature.

WILLIAM L. EVANS.
